DESIGN FOR A FINGER RING

Benjamin Axel, Brooklyn, N. Y.

Application April 10, 1939, Serial No. 84,165

Term of patent 3½ years

To all whom it may concern:

Be it known that I, Benjamin Axel, a citizen of the United States, residing at Brooklyn, in the county of Kings and State of New York, have invented a new, original, and ornamental Design for a Finger Ring, of which the following is a specification, reference being had to the accompanying drawing, forming part thereof,

Fig. 1 is a front view of a finger ring, showing my new design.

Fig. 2 is a side view thereof.

I claim:

The ornamental design for a finger ring, substantially as shown.

BENJAMIN AXEL.
